UNITED STATES PATENT OFFICE.

LEONARD DAHLGREN, OF ATTLEBORO, MASSACHUSETTS, ASSIGNOR TO TILLKWIK COMPANY, OF ATTLEBORO, MASSACHUSETTS.

CIGARETTE CASE.

Application filed February 21, 1921. Serial No. 446,770.

To all whom it may concern:

Be it known that I, LEONARD DAHLGREN, a citizen of the United States, residing at Attleboro, in the county of Bristol and State 5 of Massachusetts, have invented new and useful Improvements in Cigarette Cases, of which the following is a specification.

This invention relates to certain new and useful improvements in cigarette cases and 10 the primary object thereof is to provide a cigarette case which has improved means for centering the cigarette holder, the latter being pivoted between the front and back of the case.

15 A further object of the invention is to provide a cigarette case which has a holder composed of readily separable parts thereby to allow the parts to be separated either for the purpose of more easily placing the cigarettes in the holder or to clean out or remove any tobacco crumbs or the like which 20 may have accumulated in the holder.

25 A further object of the invention is to provide a holder of simplified and economical manufacture, wherein the same is composed of two parts having novel and readily separable connections between the ends thereof and more specifically to allow the ends to be connected by a snap action, and 30 likewise easily disconnected.

Further and other objects will be later set forth and manifested in the course of the following description.

In the drawings:

35 Figure 1 is a plan view with the parts in open position;

Figure 2 is a section on line 2—2 on Figure 1, and

40 Figure 3 is a bottom edge view with the parts in closed position.

In proceeding in accordance with the present invention a case is employed composed of similar front and back members 1 and 2 connected by any suitable form of 45 latch 3. The parts 1 and 2 are provided with hinged knuckles 4 mounted on the usual pintle 5. The cigarette holder is composed of two similar sections or parts 6 and 7 having complementary seats 8 which 50 conjointly form individual cigarettes compartments 9. The members 6 and 7 have hinge knuckles 10 which are mounted on the pintle 5 so that each of the members can pivotally move about the pin 5, either 55 independently of the other. For the pur-

pose of centering the holder when the case is in full open position as depicted in Figure 1 of the drawings, approximately L-shaped stops 11 are employed for the member 6 and similar stops 12 for the member 7. These stops are secured at one end to the adjacent cover 1 or 2 so that their opposite ends project upwardly into the case to abut the bottom edges of the respective holder parts 6 and 7 as shown in Figure 65 1 of the drawings.

The ends of the holder parts 6 and 7 are curved as indicated at 13 and 14 and are formed to interengage or snap one over the other thereby allowing of the ready separation thereof, either for the purpose of cleaning out any tobacco crumbs or the like or for the purpose of more easily permitting cigarettes to be placed in the holder without mashing or cutting or otherwise marring the 75 cigarettes ends, such as frequently occurs when the cigarettes are inserted with the parts 6 and 7 in the position as shown in Fig. 1 or 2. In addition the necessity of soldering or otherwise fixedly connecting 80 the ends of the parts 6 and 7 together, is eliminated. It will be seen that a pair of stops is provided for each of the parts 6 and 7, so that when the parts are in the position of Fig. 1 the cigarette holder cannot be 85 moved in any direction, or in other words is held fixed in position.

From the foregoing it will be seen that the device can be economically produced and that the holder sections are capable of 90 ready separation and connection and are positively held together as well as against all movement in a centered position when the case is opened fully as shown in Figures 1 and 2.

Having thus described my invention, what I claim as new and desire to secure by Letters Patent is:—

1. In a cigarette case, hingedly connected front and back members, a holder composed 100 of hinged sections having slotted bottoms, and L-shaped stop members for each section, said stop members being secured at one end to the bottoms of the respective front and back members and having their opposite ends extending into the case and through the slots of the bottoms of the sections to hold the latter against all movement 105 when the case is in fully opened position.

2. In a cigarette case, hingedly connected 110

front and back members, a holder composed of a pair of sections hinged together to receive the cigarettes therebetween, each end of each section being curved throughout its 5 width and formed to engage over the adjacent end of the adjacent section so as to provide a frictional latch action throughout the widths of the sections.

3. In a cigarette case, movably connected 10 front and back members, and a holder composed of a pair of sections hinged together to receive the cigarette therebetween, each end of each section having means of substantially identical construction formed to 15 interengage and to snap into and out of engagement with each other.

4. In a cigarette case, hingedly connected 20 front and back members, a holder composed of hinged sections having slotted bottoms, and stop members for each section secured 25 at one end to the front and back members and having their opposite ends extending through the slots of the bottoms of the sections to hold the latter against all movement when the case is in fully open position.

5. In a cigarette case, hingedly connected 30 front and back members, a holder composed of hinged sections having slotted bottoms, and stop members secured to the outer faces

of the bottoms of the front and back members and extending through said bottoms and upwardly through the slots of the bottoms of the sections to hold the latter against all movement when the case is in 35 fully open position.

6. In a cigarette case, hingedly connected front and back members, a holder composed of hinged sections having inwardly extending bottoms provided with outwardly opening slots, and stop members for each section secured to the front and back members and having parts extending through the slots of the bottoms of the sections and engaged 40 with the adjacent edge portions of the bottom of the adjacent sections.

7. In a cigarette case, hingedly connected 45 front and back members, and a holder composed of a pair of sections hinged together to receive the cigarette therebetween, each end of each section having curved interengaging parts to snap into and out of engagement with each other.

In testimony whereof I have signed my 50 name to this specification in the presence of 55 two subscribing witnesses.

LEONARD DAHLGREN.
